US00D957270S

(12) **United States Design Patent** (10) **Patent No.:** **US D957,270 S**
(45) **Date of Patent:** **** Jul. 12, 2022**

(54) **TIMER FOR COMPETITIONS**

(71) Applicant: **GUANGZHOU GANYUAN INTELLIGENT TECHNOLOGY CO., LTD.**

(72) Inventor: **Ganyuan Jiang**, Guangzhou (CN)

(73) Assignee: **GUANGZHOU GANYUAN INTELLIGENT TECHNOLOGY CO., LTD.**, Yiwu (CN)

(**) Term: **15 Years**

(21) Appl. No.: **29/772,679**

(22) Filed: **Mar. 3, 2021**

(51) LOC (13) Cl. **10-03**

(52) U.S. Cl.

USPC **D10/40**; D21/324
